UNITED STATES PATENT OFFICE.

AXEL JOHNSON, OF OAKLAND, CALIFORNIA.

ELECTRIC HEATER.

Application filed July 29, 1925. Serial No. 46,705.

This invention relates to electric heaters and particularly to a heating unit adapted for mounting in an air supply conduit for supplying heated air to buildings or for 5 other desirable purposes.

An object of the invention resides in providing a heating unit comprising an open framework mounting a plurality of heating elements in tiers or banks wherein the elements in each bank are in spaced relation and arranged alternately with respect to the heating elements in adjacent banks so that air passed through the framework will become thoroughly and uniformly heated.

15 A further object of the invention resides in providing a special framework construction for the heating elements which removably mount the same therein in convenient and accessible relation.

20 Another object of the invention resides in providing a heating element of special construction having a substantially flat rectangular form provided with end recesses receiving the terminal connections for the 25 heating element which is wound in a continuous groove formed throughout the area of the element.

The invention comprehends other improvements residing in the construction and 30 arrangement of parts as more particularly described in the following detailed description and in the claim directed to a preferred construction of the invention, it being understood, however, that various changes in 35 the size, shape, and arrangement of these parts may be made without departing from the spirit and scope of the invention as herein set forth.

In the drawings forming a part of this 40 application,

Fig. 1 is a side elevation of a heating conduit showing the manner of mounting the heating unit therein and also showing diagrammatically the circuit connections and 45 switches for controlling the energy supply to the banks of heating units.

Fig. 2 is an enlarged plan view of the 50 rack showing the heating elements mounted therein and the air conveying conduit in section.

Fig. 3 is a side elevation of the rack and the heating elements, portions of which are broken away and shown in section.

Fig. 4 is an end elevation of the structure 55 shown in Fig. 3.

Fig. 5 is a detailed longitudinal section or

a substantially large scale through one end of one of the heating elements.

1 indicates an air conduit adapted to supply air for any suitable purpose which is 60 provided at 2 with an air intake and a fan 3 for forcing air through the conduit. A door is provided at 4 giving access to a portion of the conduit adjacent to the fan 3 so that the heating unit indicated in dotted 65 lines by the numeral 5 may be conveniently inserted or removed from said conduit in the rear of the fan 3 and which is adapted for uniformly heating the air being forced therethrough by the fan. In the zone of the 70 conduit receiving the heating unit 5 the same is lined throughout the inner surface with insulating material indicated at 6.

The heating unit includes a main frame 75 made up of a plurality of longitudinal angle bars 7 connected by the vertical and horizontal end bars 8 and 9, respectively. A plurality of supporting bars 10 are mounted on the end bars 8 and extend longitudinally 80 along each side of the frame. These bars are provided with notches in their upper edges as indicated at 11 for receiving and holding the spreader bars 12 in position. These spreader bars are of inverted U-shape 85 and extend transversely of the main frame for support upon corresponding horizontal supporting bars 10 at the opposite sides of the frame as clearly shown in Fig. 4. These spreader bars mount a plurality of pins 13 which project laterally from one side thereof and receive and support the heating elements 14 thereon. These spreader bars are 90 arranged in pairs in which the pins 13 project in opposed relation into the sockets 15 formed in the upper edges of the ends of the 95 heating elements 14 as clearly shown in Fig. 3. In this way it will be noted that the spreader bars are removably mounted in the notches in the supporting bars 10 and removably but yet rigidly mount the heating 100 elements 14 in predetermined spaced relation within the confines of the main frame.

As shown particularly in Fig. 2 the heating elements in different banks or between different pairs of spreader bars are mounted so 105 as to be in staggered relation relative to the direction of flow of air through the frame.

Each of the heating elements are of similar construction and comprise a substantially flat molded body of suitable insulating material. These elements are of substantially 110 rectangular formation and have the upper

and lower edges rounded as illustrated in the drawings. The end portions are provided with cut out sections or recesses 16 which provide end lugs 17 for receiving the terminals 18 for the heating element. These molded bodies are provided with transversely extending grooves 19 in the faces thereof which are interconnected around the curved edges so that a continuous substantially spiral groove is formed from end to end of the elements in which the grooves in one side and at one end are arranged in a substantially vertical or transverse relation in the body of the element while the grooves progressing towards the opposite end on the same side of the body are formed therein at successively increasing angles. The grooves on the opposite side of the body are formed in the same manner with substantially vertical or transversely extending grooves while at the opposite end the said grooves incline successively, these grooves being arranged in the reverse relation to the grooves in the other side. The heating element 20 is formed of a substantially helical resistance wire laid in said grooves 19 and secured therein by suitable fireproof material which firmly cements the heating coil in the grooves for the purpose of preventing sagging and the like. The particular formation of the grooves permits the use of the entire area of the body of the element for receiving portions of the heating element therein in order that a heating coil having a maximum length may be wound over substantially the entire area in order that the element may at the same time be made of small size. The particular relation of the grooves as above described aids in providing a heating element structure of minimum size and at the same time carrying the maximum length of heating coil. The heads of the binding posts 18 are slotted and receive the ends of the heating element 20 from the end portion of the groove in the body of the element which head portion is swaged over the end of the wire 20 of the heating coil for effectively retaining the heating coil in direct electrical connection with the binding post without other securing means. Lock nuts 21 secure the binding posts 18 in the body of the element while the bus bars 22 having a plurality of openings in spaced relation fit over the ends of the binding posts 18 and are rigidly connected thereto by the use of additional lock nuts so that the several heating coils on the heating elements are connected in the circuits made with the bus bars in parallel. The ends of the bus bars 22 are formed with sockets 23 which receive the ends of the cables 24 used for connecting the several banks of heating elements with the controlling switches 25 which may be located re-

mately to the main framework and the heating unit. A main control switch 26 may 65 also be provided for controlling the connection of the heating elements with sources of power of different voltage or from different sources. As shown particularly in Fig. 2 the cables 24 extend through insulating sleeves 27 mounted in the side of the conduit 1 and extending through insulating section 6.

As shown in the drawing a plurality of heating elements 14 are mounted between 75 each pair of spreader bars to form a bank of heating elements which are removably supported on the bars 10 and opposite sides of the main frame. As shown there are a plurality of banks arranged horizontally in 80 which the heating elements of each adjacent bank are mounted in staggered relation to produce even heating of air flowing through the frame. It will also be noted that there are a plurality of vertically arranged banks 85 of heating elements supported by different pairs of bars 7 in spaced horizontal planes.

In this way a substantially open and readily disassembled structure is provided for a plurality of banks of heating units in 90 which the units themselves are removably mounted between pairs of spreader bars while the spreader bars are removably seated in the notches of the supporting bars 10. A further feature of the invention resides in 95 the construction of the heating element which is provided with recesses for removably receiving the pins of the spreader bars and provided with cut out portions in the ends mounting the terminals for the heating 100 coil while at the same time utilizing the entire surface of the body for receiving a heating element in a predetermined manner.

What is claimed is:

A heating unit comprising an open frame work having a plurality of parallel spaced horizontal bar members disposed in superimposed pairs at opposite sides of the frame, pairs of parallel supporting bars removably resting in predetermined spaced relation at 110 opposite ends on opposing bar members of the respective pairs, a plurality of elongated heating elements disposed in parallel spaced relation between said pairs of supporting bars and secured at their ends thereto forming with said supporting bars horizontal and vertical rows of batteries of heating units, each horizontal row being independently removable from said frame, the heating element between each adjacent pair of supporting bars being positioned in staggered relation with one another.

In testimony whereof I have signed my name to this specification.

AXEL JOHNSON,
